(57) **CLAIM**

The ornamental design of a headrest pillow, as shown and described.

DESCRIPTION

FIG. 1 is a perspective view of a headrest pillow, showing my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a perspective view of the headrest pillow deployed on an environment of a couch.

The broken lines in the drawings are directed to environment and are for illustrative purposes only; the broken lines form no part of the claimed design.

1 Claim, 8 Drawing Sheets
